UNITED STATES PATENT OFFICE.

FREDERICK WALTER DENNIS, OF BEATRICE, NEBRASKA.

BRICK-KILN.

SPECIFICATION forming part of Letters Patent No. 396,733, dated January 29, 1889.

Application filed May 19, 1888. Serial No. 274,402. (No model.)

To all whom it may concern:

- Be it known that I, FREDERICK WALTER DENNIS, a citizen of the United States, residing at Beatrice, in the county of Gage and State of Nebraska, have invented certain new and useful Improvements in a Double Brick and Tile Kiln; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.
- My invention has relation to brick and tile kilns; and it consists in the novel construction and arrangement of its parts, hereinafter fully described in this specification, and set out in the claims.
- In the accompanying drawings, Figure 1 is a side elevation of the kiln. Fig. 2 is a view looking down into the bottom of body of the kiln, the top being cut off at the line xx . Fig. 3 is a longitudinal sectional view of Fig. 1, cut on the line yy . (Shown in Fig. 2.) Fig. 4 is a view looking down on the under part or base of the kiln, showing the man-holes, fire-pits, and fire and heat flues. Figs. 5 and 6 are detail views.
- A represents the round part of the kiln with a downdraft made of common brick when the kiln is to burn common brick; but when it is built to burn tile or fire brick the inside must be built of fire-brick.
- The round part of the kiln represented in the accompanying drawings has four flame-pockets, 2, and one flame-wall, 3, which wall fills the place of two flame-pockets. These flame-pockets are placed an equal distance from each other of about twelve feet. Said pockets are about two feet deep, four feet wide, and seven feet high. Said pockets have each five heat-holes—three in front and one on each side. The heat passes up through said pockets and through said holes and out of the top of said pockets before it can pass through to the center of the material that is being burned in the kiln.
- The bottom of the kiln is made with flues 4, radiating from the center to the outside, and shorter flues also radiating from the center to the inside of the wall, with short cross-flues 4

running close to the said wall. These flues are about one foot deep by about one foot wide, and are entirely independent of the said fire-boxes.

The bottom of the kiln is built of brick and the flues 4 are also built of brick. Underneath the floor D, immediately above the dotted line zz , in the center of the bottom of the kiln, is a pit, 5, about four feet in diameter by four feet deep, into which all of the flues run. The said pit is for the purpose of letting a man into when cleaning out the flues. The main flue 6 also starts from said pit and runs thence through the second kiln B C, and thence into the stack E.

The main kiln A is run by six fire-boxes, 7, on the outside of the wall of said kiln, and are built of good brick and are arched over by arches b. These fire-boxes are about three and one-half feet deep by about four feet wide, and are about four feet ten inches long, and about three feet four inches of their length runs under the kiln, leaving about one foot and one-half on the outside of the wall. These figures give the clear inside of the said boxes. At the outer end of each of the said fire-boxes 7 is a man-hole, 8, about four by four feet, and about four feet deep. These man-holes are for the purpose of clearing out the ashes, &c., and to give the necessary air for draft. At the bottom of the said fire-boxes are placed two cross-bars, which are laid stationary in the wall at the time of building the said boxes. One is laid flush with the outside ends of the boxes, and the other is laid one foot from the inside end of the same, leaving a space, 9, between them and the bottom of end wall of the said boxes, so as to leave sufficient room for several straight fire-bars, 10, pushed in over the said cross-bars, which form the bottom of the said fire-boxes. Under each of these fire-boxes is a pit about four feet wide by about four feet ten inches long and about one and one-half foot deep for the ashes to fall into. The fuel that is burned in said fire-boxes is shoveled into them through the small openings d through the arch b over the top of the fire-boxes close to the walls of the kiln, which are about one foot square. When fired, there must be a large fire-brick or iron door laid over each of these openings, so as to keep in the heat.

The main kiln A has two doors, 11, opposite each other, one on each side of the kiln. These doors are to provide for the loading and the unloading of the kiln, and are built 5 up and plastered every time the kiln is filled for burning. The small openings 12 are to look through the kiln while burning to see when the material is sufficiently burned.

B C is the other part of the kiln, which is 10 oblong and is also arched over. It is about thirty feet long, about twelve feet wide, and about twelve feet high. It has a flame-wall, e, about two feet from the square part of the round kiln A.

15 As stated above, the main flue 6 starts from the center 5 of the round kiln, and the heat and draft pass up over said flame-wall and through the material in the part B of the said oblong division. On the top of said 20 flame-wall is a slanting cap, 13, which is to divide the heat as it comes from the said main flue 6. That part of the main flue 6 between the fire-wall 3 of the part A of the kiln and its square part is covered by a slanting 25 cap, f, so that the heat which passes along said main flue does not pass up at this point into the main kiln, but is carried into the oblong part up through an opening, f', under the slanting cap f. The said flame-wall e in 30 the oblong kiln acts on it the same as the flame-wall 3, and flame-pockets 2 act on the round kiln, giving a downdraft. The said oblong part B C of the kiln has another flame-wall, g, across its center, which divides the 35 same into two equal parts. Near the bottom of said wall g are three openings, h, for the purpose of conducting a part of the heat and draft into the other or second part, C, of said oblong division, and at the top of this said 40 wall g are four openings, h', to take the balance of the heat and discharge it as a down-draft through the openings 14 in third and last apartment.

On each side of the kiln B C are two fire-boxes 7, exactly similar to the other fire-boxes 7 above described. Said fire-boxes are 45 side by side, but are separated by a wall, and are for the purpose of burning the smoke and to assist in burning the kiln equal with 50 the material in the round kiln. In the corners of the parts B C, against the flame-wall g, are four flame-pockets—two on each side of said wall. In the apartment next to the round kiln the said pockets f² are about four 55 feet high and about four feet wide and about two feet deep, and in the third and last apartment, C, the said pockets are about seven feet high. The reason why these first two pockets just mentioned are only four feet high is 60 that only small fires are needed in this part of the kiln, and also to burn the lower material. If they were any higher, the four upper openings, h', in the division-wall g would take too much of the heat from this part of the 65 kiln.

In the extreme front end of the kiln next

the smoke-stack E are three small flue-holes, 14, the center one being over the main flue 6 and leading into the smoke-stack. The other two are side flues or canals leading into the 70 main flue. These flues 14 are for the purpose of drawing the heat to the extreme corners of this part of the kiln. To the last-mentioned fire-boxes are dampers 15—two on each side of the oblong part of the kiln—to regulate the 75 fires, as the draft here is so great as to interfere with the drafts in the round kiln if not regulated by dampers. Near the smoke-stack E is a damper, 16, in the main flue 6 operated by a ball and chain. This damper is to regulate 80 the whole system of drafts.

The walls of the oblong part B C of the kiln should be heavier than the wall of the round part, for the reason that it has not the same facility for expansion, and should be not 85 less than two feet thick. The walls are also protected by six abutments, 17—two against each side and two against the forward end. At the rear end of the oblong part of the kiln, next the round part, are two heavy iron 90 rods or bars, 18, (see Figs. 5 and 6,) built in the cross-wall 23 across the kiln in the masonry and on a line with the iron bands 19 that surround the round kiln. Said rods or bars 18 have an eye on each end, into which 95 the bands hook and double back on said bands, and are secured by bolts and nuts 22. Said bands have a buckle-nut, 20, or similar screw arrangement at the front part of the kiln for tightening or loosening them, as the 100 case may require, during the contraction and expansion of the kiln while burning.

Should the locality where the kiln is built be very damp and wet, so as to interfere with the fire-boxes being dug in the ground, they 105 may be built near the top of the ground and the flues may be built wider and not so deep, and they will answer nearly the same purpose.

The smoke-stack E is about five by five feet 110 inside, with an air-chamber inside to prevent its burning, and is fifty or more feet high.

The dimensions as given above are intended more to give the proportionate dimensions of the several parts than to determine 115 the size of a kiln.

A kiln may be built much larger or smaller than the one just described; but the relative proportions should be observed.

Should it be advisable to build a pair of 120 these kilns—one on either side of the smoke-stack—the smoke-stack must be built proportionally larger, with a dividing-wall up through the center.

Both parts of the kiln A and B C are arched 125 over, and have openings 21 near the top to allow for cooling off when the burning is finished; but while the burning is going on said openings must be closed up air-tight.

The flame-walls may be made of raw material 130 every time the kiln is filled, thereby not only being less expensive in first cost but

giving much more burned brick in the same space than if the walls were made permanently of burned brick.

Having described my invention, what I claim as new, and desire to secure by Letters Patent, is—

1. In a kiln, substantially as shown and described, the heavy iron bars 18, built in the cross-wall 23, iron bands 19, their tongue 10 hooking into the eyes of said bars, doubling back on said bands, and secured by bolts and nuts 22, and buckle-nuts 20, all substantially as shown and described, and for the purposes set forth.

2. In combination with the round part A, 15 substantially as described, and having the main flue 6, opening f', and cap f, the oblong kiln B C, substantially as described, having the flame-wall e, and slanting cap 13, substantially as shown and described, and for the 20 purposes set forth.

In testimony whereof I affix my signature in presence of two witnesses.

FREDERICK WALTER DENNIS.
